UNITED STATES PATENT OFFICE.

FREDERICK M. BENNETT, OF NEW YORK, N. Y.

INCANDESCENT LAMP.

No. 898,715.

Specification of Letters Patent. Patented Sept. 15, 1908.

Application filed March 6, 1908. Serial No. 419,538.

To all whom it may concern:

Be it known that I, FREDERICK M. BENNETT, a citizen of the United States of America, and a resident of New York, in the county and State of New York, have invented a certain new and useful Incandescent Lamp, of which the following is a specification, the same being a full, clear, and exact description of the invention, such as will enable others skilled in the art to which it appertains to make and use the same.

This invention relates to the construction of an electrical glow-lamp, and in particular to a novel forming or looping of the filament 15 of the lamp for the purpose of securing a more advantageous distribution of the light, as will be hereinafter more fully described, reference being had to the accompanying drawings in which

Figures 1 and 2 are side elevations of a lamp constructed according to my invention, and Fig. 3 is a plan view of the same.

The bulb A of the lamp may be of any ordinary or suitable construction and has a 25 mount *a* through which the leads *a'* are passed.

The filament B consists of a plurality of loops located relatively approximately at right angles to each other, and, as ordinarily 30 constructed, it comprises one or more practically vertical central convolutions *b*, and a plurality of approximately horizontal loops *b'*, the number of the convolutions being varied according to the voltage at which the 35 lamp is to be run, and also according to the amount of luminous surface desired to be presented when viewed from the lower or tip end of the lamp.

In the embodiment shown in the drawings, I employ two approximately horizontal loops on each side of the longitudinal axis of the lamp, but, obviously, one of the convolutions on each side of the vertical loop may be dispensed with, if preferred.

By employing the above described convolutions, the light is manifestly thrown not only sidewise from the lamp, but an increased light downward is also obtained.

One or more anchors *a²* may be used, which 55 are ordinarily secured to the mount *a*, and attached to the filament intermediate of the ends thereof, whereby the filament is practically rigidly held in position, and is therefore not liable to become broken by reason of jars or shocks.

In the operation of assembling the parts of the lamp, the filament, after it has been formed and carbonized, has to be attached to the leads and also to the anchors. In doing this it is not practicable to present filaments 60 in the various completed lamps, made according to this invention, of the same identical shape in every particular, inasmuch as drawing the same down for attachment to the leads and anchors will necessarily throw 65 the loops in somewhat different shapes in different lamps, but in all such cases, the main characteristics and approximate relative position of the loops will be maintained. It is therefore manifest that the size, number, 70 contour or shape, and relative position of the loops of the filament may be varied, so long as the essential feature of the lamp is preserved, namely, the use of a substantially vertical loop to throw the light sidewise, in 75 conjunction with another angularly disposed filament loop to throw the light preferably downward and in the direction of the longitudinal axis of the lamp.

My improved spread coil filament is not 80 only very efficient in affording a perfect diffusion of the light, by the use of a vertical loop and loops positioned at right angles thereto, but is of increased utility commercially, as by its use a uniform illumination is 85 secured, inasmuch as the light may be equally thrown in every direction, and particularly downward where the illumination is generally required to be the strongest, as the filament is so shaped as to present a 90 greater amount of luminous surface at the end of the lamp where the projection of the rays is downward.

I wish it understood that I do not desire to be limited to the exact details of construction shown and described, for, obviously, 95 modifications will occur to a person skilled in the art.

What I claim as my invention, is:—

1. In an incandescent lamp, a spread coil 100 filament comprising a substantially vertically disposed loop, and a plurality of loops each constructed and arranged to lie in a relatively approximately horizontal direction the planes of the latter loops intersecting 105 the longitudinal axis of the lamp.

2. In an incandescent lamp, a spread coil 110 filament comprising a substantially upwardly disposed loop to throw the light sidewise from the lamp, and a loop at a relatively ap-

proximate right angle to the first loop to throw the light substantially in the direction of the longitudinal axis of the lamp.

3. In an incandescent lamp, an upwardly disposed filament loop, and a plurality of outer loops sidewise disposed so that the plane of each of which latter loops intersects the plane of the central loop at an angle.

4. In an incandescent lamp, an upwardly disposed filament loop, a sidewise disposed loop the planes of which two loops are constructed and arranged to intersect at an angle, and an anchor for the upwardly disposed loop, the point of anchorage lying approximately in the plane of the side loop.

5. In an incandescent lamp, an upwardly disposed filament loop, anchors located on each side of the same at the base thereof, the said filament being turned outwardly from said anchor points and then deflected in a substantially circular form, and curved downward and fastened to the leading in wires approximately vertically below the anchor points to form a plurality of sidewise dis-

posed loops, one of each lying in a plane at 25 an angle to that of the central loop, the said planes having an approximate common line of intersection.

6. In an incandescent lamp, an upwardly disposed filament loop, anchors located on each side of the same at the base thereof, the said filament being turned outwardly from said anchor points and then deflected in a substantially circular form, and curved downward and fastened to the leading in wires 35 approximately below the anchor points to form a plurality of sidewise disposed loops, one of each lying in a plane at an angle to that of the central loop.

In testimony of the foregoing specification, I do hereby sign the same in the city of Philadelphia, county of Philadelphia and State of Pennsylvania, this 29th day of February 1907.

FREDERICK M. BENNETT.
